UNITED STATES PATENT OFFICE.

JAMES WILLIAM DECKERT, OF OAKVILLE, ONTARIO, CANADA.

MACHINE FOR SPLITTING RAW HIDES AND SKINS.

No. 856,395.

Specification of Letters Patent.

Patented June 11, 1907.

Application filed September 5, 1905. Serial No. 276,987.

To all whom it may concern:

Be it known that I, JAMES WILLIAM DECKERT, a citizen of the United States of America, residing in the town of Oakville, in the county of Halton, in the Province of Ontario, Canada, leather-splitter, have invented certain new and useful Improvements in Machines for Splitting Raw Hides and Skins, of which the following is a specification.

10 My invention relates to improvements in machines for splitting raw hides and skins, and the objects of my invention are firstly, to split raw hides and skins; secondly, to split both raw and tanned hides and skins 15 quicker than is now possible with existing machines; thirdly, to get a cut of uniform thickness; fourthly to set or work the raw hide out and hold it in that position up to the point where it is brought in contact with the 20 knife, and fifthly to provide accurate adjustment for the knife, and it consists of the parts hereinafter described and more particularly set forth in the claims.

Figure 1 is a front-side elevation of my 25 machine, parts being broken away. Fig. 2 is a rear-side elevation. Fig. 3 is a vertical section on the line *a*—*b*, Fig. 1. Fig. 4 is a vertical section on the line *c*—*d*, Fig. 2. Fig. 5 is a vertical section on the line *e*—*f*, Fig. 2. 30 Fig. 6 is a plan view of the member co-operating with the cylinder. Fig. 7 is an enlarged cross-section through one of the rings of said member. Figs. 8 and 9 are enlarged details hereinafter referred to. Fig. 10 is an enlarged perspective view of part of a clamping-plate, and Fig. 11 is a vertical section 35 similar to Fig. 3, certain parts being removed.

In the drawings like characters of reference indicate corresponding parts in each figure.

Before the hides or skins can be cut by the belt-knife machines now on the market, they must be tanned and passed through a setting 45 out or stoning-machine. They are then mounted on a reel co-operating with the belt-knife splitting-machine and fed therefrom to the knife. During the feeding operation of the work same must be kept spread out by an 50 attendant at each side of the machine. Now by my machine I can take the work as it comes from the pickle, lime or bate and successfully split it. By means of my machine I can also split tanned hides and skins that

have been previously stoned out or set out, 55 as will be hereinafter more particularly explained.

The drum, cylinder, or roller, carrying the work, and the member constructed of a plurality of revolving disks or rings, revolve at 60 the same peripheral speed so that the work passing therebetween will be fed to the belt-knife through the medium of both of its surfaces which travel at the same speed: so feeding the work to the belt-knife absolutely prevents it from being bagged or cockled up just before it is brought to the knife, thus enabling the machine to produce a split of uniform thickness. Where the work is fed to the knife through the medium of only one of 70 its surfaces, it is apt to bag or cockle up just before it is brought to the knife; besides as one surface of the green work moves in advance of the other, the fibers are longitudinally stretched and through the action of the 75 belt-knife a great deal of glutinous matter is liberated from the cells therein, thus gumming up the knife and preventing the machine from commercially splitting raw or green hides. In connection with the splitting of raw or green hides by my machine, the cylinder works or sets out the hide absolutely flat upon the non-stretchable surface of the drum or cylinder, and during this process more or less longitudinally condenses the 85 fibers thereof; the work adheres to the drum and is carried thereby in this state underneath the member constructed of a plurality of rotating disks or rings which keep the work in its set-out or worked-out position, 90 and in a condensed or hard state, by additionally, substantially longitudinally, compressing the fibers and only releasing the work at the splitting edge of the knife. Therefore, through the action of my cylinder 95 and said member the fibers are held in a condensed position and presented more or less at right angles to the knife, thus explaining the reason why the work is more easily split than when it is fed to the knife 100 through the medium of only one of its surfaces.

A is any suitable rotary drum, cylinder, or roller which is mounted by the arms *A*¹ on the shaft *B* held in bearings in any suitable head-blocks *C* and *C*¹. This drum, cylinder 105 or roller may be of any suitable construction. According to the construction shown, the drum is constructed of an inner portion *D*

made of wood or other similar material covered on the outside with metal E, preferably brass, so as to provide a positive, level bed and prevent any possibility of rust coming 5 in contact with the work and also to provide an unstretchable bed for the work to rest upon. When the work to be split is raw I use in conjunction with the drum any suitable cylinder E¹ which is composed of its 10 shaft E² by means of which it is held in suitable adjustable bearings e held in the slots e¹ in the head-blocks C and C¹, and a suitable foundation E³ keyed to said shaft. Suitably held in said foundation are a plurality of 15 blades E⁴ which are constructed of material having sufficient flexibility to enable them to yield up on the thick portions of the work and to follow down and press on the thin portions thereof, thereby working or setting it 20 out and keeping it close upon the drum. These blades will be preferably constructed of rubber, although I may use any other suitable material that will give the required action. As will be seen from Fig. 1, the blades 25 are constructed spirally and that one-half of the cylinder will stretch or set out the work in one direction, and the other half perform the same function in the other direction. This setting-out or stretching action of the 30 cylinder upon the work is of course well known.

e² is the power-pulley for the cylinder.

F is any suitable clamping bar having sliding movement on the guides F¹ secured to 35 the drum. As will be seen from the drawings, the drum is provided with a longitudinal slot F² in which is placed one end of the work F³ so as to rest against the teeth or projections f secured to or forming part of the 40 plate F⁴ which is attached to the drum. By means of the arm F⁵ and eccentrics F⁶ secured to the rock-shaft F⁷ (held in suitable bearings F⁸ secured to the drum) and the arms F⁹ (which are connected at their upper ends to 45 the clamping bar by the pins G and in the lower ends of which said eccentrics operate), said clamping bar is moved on the guides F¹ so as to release the work or retain it in position.

By means hereinafter described, the drum 50 is revolved in the direction indicated by arrow and, as the work passes underneath the cylinder E¹ it is subjected to the action of the blades thereof and set out. In order to maintain the work in this set-out position I 55 provide a member which I will term a ring-roller G¹, hereinafter particularly described, and which is made up of a plurality of sections constructed so as to conform to the varying thicknesses of the work and keep it 60 set out and firmly upon the drum up to the point where the work is brought in contact with the knife, releasing it just at point of cutting. Mounted in suitable brackets C² and C³ are the knife-wheels C⁴ on which operates the belt-knife C⁵. By means hereinaf-

ter described, these knife-wheels are operated, consequently operating the belt-knife C⁵ so that as the drum revolves and brings the work in contact therewith, a cut of the required thickness will be taken therefrom and 70 will pass off in the direction indicated by dotted lines in Figs. 3 and 11. Each time the drum is revolved of course the work is split.

By means of the hand-wheels G² the bearings e of the cylinders E¹ are raised or lowered so as to regulate the pressure of said cylinder upon the drum. The ring-roller G¹ consists of a plurality of members which are constructed as follows: Passing through 75 these members is a common shaft G³ which is held in the adjustable bearings G⁴ operating in the slots G⁵ formed in the head-blocks C and C¹. By means of the hand-wheels G⁶ said adjustable bearings G⁴ are raised or lowered so as to adjust the position of the ring- 80 roller G¹. The outer portion of each member consists of a ring G⁷ intermediate which and the shaft G³ is a layer of resilient material G⁸ preferably rubber. As the ring-roller 85 G¹ will be held with sufficient pressure upon 90 the work, it will be understood that the individual members composing same will follow the varying thickness of the work, that is, have similar action in this respect to the blades of the cylinder E¹, and thus maintain 95 the work in the set-out or stretched position given it by said cylinder. Although not essentially forming a separate part therefrom I preferably key to the shaft G³ a disk G⁹ for 100 each individual member of the ring-roller between which and the ring G⁷ is the resilient material G⁸. It will be noticed that the inner perimeter of the ring G⁷ and the outer perimeter of the disk G⁹ are serrated as shown at G¹⁰ and G¹¹, thus insuring the positive circular movement of all these parts, with their 105 shaft. The ring roller revolves at the same peripheral speed as that of the drum, thereby feeding the work to the belt-knife through the medium of both of its surfaces, which 110 travel at the same speed. Of course by different means or construction other than the serrations before mentioned, I may obtain 115 the result desired.

H are tie-plates bracing the upper portions 115 of the head-blocks together. As the pressure exerted against the ring-roller G¹ will be quite considerable, I prefer to use means to prevent same from being moved out of alignment and thus insure it coming in contact with the 120 work for its whole length. My preferred means for this purpose consists of stiff plates I secured to the tie-plates H and extending one on each side of the ring-roller as shown in 125 Figs. 3 and 11. The lower end of these plates of course do not interfere with the operation of the ring-roller. If desired, these plates may be made adjustable. In Figs. 3 and 11 I have shown one of the plates provided with slots h through which operates a screw h¹. In 130

order to raise or lower this plate it will be necessary to loosen this screw and tighten it up when the required adjustment is obtained. As the constant friction between the ring-roller and these plates will wear the plates, I prefer to provide screws h^2 operating through the tie-plates H and bearing at their outer ends against the top inner sides of said plates so as to maintain them at the required angle. By so adjusting these plates I find that I can regulate the wear of their lower ends more uniformly than otherwise. One of said plates only is shown adjustable, as it was not considered necessary to duplicate this construction for the other plate as its application thereto will be readily understood by one skilled in this art.

The cylinder is always revolving in the direction indicated by arrow, and the belt-knife is also moving in the direction indicated by arrow. By means of the pulley J on the counter-shaft E², power is conveyed to the machine.

J¹ is a standard providing the necessary bearing for the outer end of the shaft E².

J² is a gear-wheel keyed to the shaft E² and meshing with the gear-wheel J³ (having bearing on the shaft J⁴ held in the standards J⁵) by means of the intermediate gear-wheel J⁶ held in the shaft J⁷ which has bearing in the standards J⁸ one of which is shown dotted in Fig. 1.

J⁹ is a bevel-pinion keyed to the shaft J¹¹ of the associated knife-wheel C⁴. By the gearing just described, power is conveyed to the knife-wheel so as to operate the knife.

K is a pulley keyed to the shaft E² and transmitting power by means of the belt K¹ to the pulley L keyed to the shaft M held in suitable standards N and O.

N¹ is the lower grinder-wheel keyed to the shaft N² having bearing in the bracket N³ suitably secured to its associated head-block.

N⁴ is a pulley keyed to the shaft M which by means of the belt N⁵ transmits power to the pulley N⁶ keyed to the shaft N².

N⁷ is a pulley keyed to the shaft M which by means of the twisted belt N⁸ conveys power to the shaft N⁹ by means of the pulley N¹⁰ keyed thereon. N¹¹ is the other grinder-wheel which is operated by the shaft N⁹.

N¹² is any suitable bracket in which the shaft N⁹ has bearing and is suitably secured to its associated head-block.

N¹³ is the usual support for the knife whereby it is held in position at the point of operation of said grinder-wheels.

On one end of the cylinder-shaft B is keyed a sprocket-wheel O¹ which transmits energy by a sprocket-chain O² to the sprocket-wheel O³ keyed to the stub-shaft O⁴ having bearing in the head-blocks C¹. The energy is transmitted from this stub-shaft by means of the sprocket-wheel O⁵ keyed thereon to the sprocket-wheel O⁶ keyed to the stub-shaft O⁷

(also journaled in said head-block) through the sprocket-chain O⁸. Keyed to the shaft O⁹ is a gear-wheel O⁹ which meshes with the gear-wheel O¹⁰ on the end of the ring-roller shaft G³. 70

The above-described gearing revolves the drum or cylinder A and the ring-roller in the same direction, and the individual wheels composing the gearing are so proportioned that the ring-roller and said drum or cylinder 75 will revolve at the same peripheral speed so that by means of these two members the work will be fed to the belt-knife through the medium of its two surfaces which travel at the same speed. 80

The power-receiving end of the drum-shaft B is provided with any suitable friction-clutch P. By means of the sprocket-wheel P¹ keyed to the shaft E² and the sprocket-chain P², power is conveyed to the sprocket-wheel P³ co-operating with said friction-clutch. According to the position of the friction-clutch shown in Figs. 1 and 2, the drum is rotating. When the clutch is to be thrown out of operation, the lever P⁴ associated therewith is thrown in the direction indicated by arrow, thus enabling the drum to be stopped. I have of course shown and described suitable gearing for transmitting power to the different parts of my machine 95 in order to explain fully my invention, but it will of course be understood that I do not confine myself to any particular means for operating my machine. 100

Q is a tie-plate for additionally bracing the upper ends of the head-blocks C and C¹. Secured to or forming part of this tie-plate is a guard Q² which prevents the water and dirt thrown by the cylinder from coming in contact with the operator. I curve the lower 105 end of this guard so as to provide a trough Q³ by means of which the material collected therewithin drains off to the sides of the machine.

As the drum rotates and brings the work 110 around to the back of the machine there may be a possibility of its free end slipping therefrom and coming in contact with the knife. In case the work does fall away from the drum, I provide a guard Q⁴ secured at both 115 ends to the tie-rods Q⁵ bracing the lower portions of the head-blocks. Upon inspecting Figs. 3 and 11 it will be seen that this guard allows ample room for the passage of the knife and effectually prevents the work 120 from coming in contact therewith.

I shall now describe the knife-jaw. The head-blocks are provided with rearward-extending portions Q⁶ to which is suitably secured the jaw-bed Q⁷. This jaw-bed is pref- 125 erably adjustable. In order to make it adjustable I provide slots q in its ends Q⁸, in which operate the screws Q⁹ held in the rearward-extending portions Q⁶. Secured to or forming part of the ends Q⁸ are ribs Q¹⁰ which 130

operate in correspondingly-shaped slots Q^{11} formed in the head-blocks. These ribs operating in their slots insure the horizontal movement of the jaw-bed. By merely 5 loosening the screws Q^9 , it will be understood that the jaw-bed can be adjusted in or out.

R is the lower member of the knife-jaw and is provided near its lower front portion with a socket R^1 which has movement on the 10 ball-shaped rib R^2 secured to or forming part of the upper forward edge of the jaw-bed. Formed in the lower member R of the knife-jaw is a slot R^3 in which operates the bolt R^4 . When it is desired to tilt the knife closer to 15 the drum, the nut R^5 of the bolt R^4 is loosened, and the bolt R^6 operating through the web R^7 of the jaw-bed and normally resting against the lower member R of the knife-jaw, is screwed upward thus tilting 20 said lower member R and its associated parts around said ball-shaped rib R^2 . By means of a socket-head R^8 secured to or forming part of the bolt R^4 (which bolt extends through the web R^7) and operating in the 25 socket R^9 formed in said lower member R, the bolt R^4 is prevented from interfering with this movement. When the necessary adjustment is obtained, the nut R^5 is screwed home. In case I should desire to move the 30 knife away from the drum and nearer the ring-roller, it will be understood that it is only necessary to lower the bolt R^6 and tighten up the nut R^5 .

R^{10} are pockets by means of which the 35 attendant has free access to the bolts and nuts extending thereinto.

Of course it will be understood that by means of the construction just described for the tilting of the lower member R of the 40 knife-jaw, I am enabled to get very nice adjustment for the knife.

S is the usual plate counter-sunk in the lower member R of the knife-jaw and is secured in place by counter-sunk screws S^1 . 45 S^2 is the usual plate counter-sunk in the under side of the upper member S^3 of the knife-jaw, and is secured in place by counter-sunk screws S^4 . Between these plates the belt-knife C^5 of course operates.

50 S^5 is a narrow plate extending the length of the knife-jaw and abutting against the rear side of the belt-knife. In order to keep this plate adjustably in contact with the knife, I operate between the members of the knife-jaw, plates S^6 at stated intervals: These plates are secured to blocks S^7 in the slots S^8 of which operate the heads S^9 connected to the screws S^{10} by the constricted neck S^{11} . These screws thread through the 55 flange S^{12} of the lower member R, and by means of the lock-nut S^{13} are held in the set position. Where the blocks S^7 operate, the members R and S of the knife-jaw are cut away so as to provide a chamber S^{14} . By 60 means of this series of plates S^6 and their

adjustable connections, it will be understood that the plate S^5 can be given variable movement so as to insure the cutting edge of the belt-knife being parallel with the drum.

It will be understood that the constant 70 friction of the knife on the plates S and S^2 wears these plates until they become gradually thinner toward their front ends. The weight of the knife will naturally keep it down upon the lower plate S and as the upper plate S^2 has been also worn away, the 75 knife will not be confined thereby at worn area and will more or less wabble, rendering it impossible to obtain a proper split. In order to compensate for the wear of these 80 plates I use the following means as my preferred construction. As there are two adjustable-means similar in construction, the description of one will do for both. Threaded in the lower member R of the knife-jaw is a 85 plug T in the socket-shaped top T^1 of which operates the socket-shaped washer T^2 upon which the rearward portion of the member S^3 of the knife-jaw rests. The bolt T^3 is provided at its upper end with a socket-shaped 90 top T^4 which has movement in a correspondingly-shaped recess in the washer T^2 . To move the plate S^2 down upon the belt-knife in order to confine it properly, the bolt T^3 is loosened and the plug T is moved by means 95 of its head T^6 upward, thus shoving the washer T^2 against the under side of the upper member S^3 of the knife-jaw, the plug T^1 being previously lowered, this giving the said upper member and its plate S^2 the necessary 100 movement. Previous to this of course the bolt T^8 of the associated adjusting-means must be loosened. When the required adjustment is obtained, the bolts T^3 and T^8 are screwed home. The adjustment just described confines the belt-knife and maintains its cutting-edge in the position it assumed by reason of the wearing away of the plates S and S^2 . In order to move the cutting edge of the belt-knife back into the position where it 105 best performs its function, the lower member R of the knife-jaw is adjusted, as before described. By means of the ball and socket-joints before described and the slots in the washers T^2 and T^5 and the slot t in the lower 110 member R, the requisite construction is provided for the movement of the adjusting-means for the upper member of the knife-jaw. As there is a space T^9 between the lower member R of the knife-jaw and the 115 web R^7 of the jaw-bed, the adjusting-means for said knife-jaw are easily gotten at.

As the ring-roller G^1 keeps the work set out up to the point where same is brought in contact with the belt-knife, it will be understood that were there not adjusting-means to take up the wear of the plates S and S^2 , the 120 wobbling or uneven movement that the belt-knife C^5 would gradually acquire because of the wearing away of said plates, would make 125 130

it impossible to get a cut of uniform thickness. But by adjusting these plates the movement of the cutting edge of the belt-knife will always be parallel to the drum.

5 It will be noticed that the upper front side U of the member S³ is curved so as to offer as little resistance as possible to the passing of the split portion of the work thereover. By means of any suitable table U¹ (shown in 10 dotted lines), secured to or forming part of the jaw-bed, the split portion of the work is prevented from coming in contact with the adjusting-means for the knife-jaw.

In order to enable the drum to be adjusted 15 to or from the cylinder E¹; the ring-roller G¹, and the belt-knife, and to enable me to maintain it parallel with these parts, I mount its shaft B in any suitable adjustable bearings. According to the construction shown, 20 the head-blocks C and C¹ are provided with slots V in which operate the bearing-blocks V¹ consisting of a lower member V² and an upper member V³ connected together by screws v. In these bearing-blocks the shaft B 25 rotates. In order to keep the members V² and V³ of the bearing-blocks in position relative to their associated head-blocks, same are provided respectively with flanges v² and v³ which overlap the horizontal sides of the 30 slots V and give the necessary bearing.

W are adjusting-screws screwing through the head-blocks and upon which the bearing-blocks V¹ rest. When it is desired to move the drum upward, the screws W¹ operating in 35 the head-blocks and resting upon the top of said bearing-blocks, are loosened and the screws W screwed upward. When the necessary adjustment is given the screws W¹ are screwed down again. The head-blocks 40 are cut away at l and m so that the heads of said screws W¹ and W may have the necessary space for movement. In order to move the drum backward or forward, the lower member V¹ of the bearing-block is constructed 45 with its front side V⁴ extending upward and sufficiently in advance of the main portion of said member and the upper member V³ so as to leave a space V⁵ in which operates the head V⁶ of the screw V⁷ operating 50 through the extension V⁸ of the head-blocks.

In the front side V⁴ is constructed a vertical slot V⁹ in which operates the screw V⁷. By means of the flange or enlarged portion V¹⁰ on said screw, together with the head V⁶ (which flange and head extend beyond the 55 sides of the slot V⁴), the adjustment in and out of the screw V⁷ will move the bearing-blocks V¹.

Upon referring to Fig. 11 it will be seen 60 that I have removed the cylinder E¹. When the hide or skin has been previously tanned and set out or stoned out, it is not necessary for me to use the cylinder. Having been already set out, the work passes underneath the ring-roller G¹ and is maintained in the

set-out position during the splitting thereof by the belt-knife.

Upon referring to Fig. 1 it will be seen that I attach the hide or skin to the drum at its butt end, taking advantage of the projections 70 thereat to clamp it in position so as to reduce to a minimum the waste. I also find that better results are obtained in setting out the hide or skin when it is operated upon from the butt end to the head end.

75

In splitting-machines now on the market, the cut passes underneath the knife and the rest of the work passes above same. Now in my machine it will be understood that the cut passes above the knife and the rest of the 80 work passes underneath same.

For the purposes of interpretation of the claims and specification, the term drum therein must be read to include a roller or cylinder or any other element that will perform the 85 function performed by said drum.

When the hide or skin comes from the pickle, lime or bate the action of the cylinder in my machine will work out all dirt and lime and any other matter that must be removed. 90 therefrom.

Upon referring to Figs. 3 and 11 it will be seen that the lower member R of the knife-jaw is constructed with an inward curve where it faces the drum, thus allowing free 95 passage of the unsplit portion of the work thereby. Upon inspecting these figures it will also be seen that the jaw-bed Q⁷ is a sufficient distance away from the drum so as not to be come in contact with the work.

100

I do not confine myself to the construction herein shown and described, as same can be changed or altered in various ways without departing from the spirit of my invention.

What I claim as my invention is:

105

1. In a machine of the class described, the combination with a belt-knife, and means for operating same, of means for feeding the tanned work through the medium of its two surfaces to the knife, consisting of a rotary member carrying the work, and a member, operating above and in advance of said knife and upon said rotary member, constructed of a plurality of disks or rings having a common axis of rotation and having independent 110 movement of each other in substantially parallel planes so as to conform to the thickness of the work under manufacture, and means for causing said rings or disks to positively rotate in the same direction as said rotary member and at the same peripheral speed thereof so as to positively feed the work through the medium of its two surfaces 115 to said belt-knife.

2. In a machine of the class described, the combination with a belt-knife, and means for operating same, of a member, operating above and in advance of said knife and comprising a revolving shaft; a plurality of 120 abutting disks or rings upon said shaft; re- 125

130

silient means interposed between said rings or disks and said shaft so that said rings or disks will have independent movement of each other substantially at right angles to the shaft and in conformity with the thickness of the work under manufacture; means for causing said rings or disks to positively rotate with said shaft and yet not interfere with their movement in conformity with the thickness of the work under manufacture, and a rotary drum; the said drum and member positively rotating in the same direction and at the same peripheral speed so as to positively feed the work through the medium of its two surfaces to said belt-knife; the said member releasing the work just about at point of splitting.

3. In a machine of the class described, the combination with the jaw-bed provided at its upper forward edge with a rib circular in cross-section, of a knife-jaw comprising a lower member provided near its lower front portion with a socket—in which rests said ball-shaped rib so that the lower member may have tilting movement on said jaw-bed, and being further provided with a slot having a socket-shaped upper portion; an adjusting screw held in said jaw-bed and operating against said lower member; a screw provided with a socket-shaped head operating in the socket-shaped top of the slot in said lower member and held in said jaw-bed whereby said lower member is held in its adjusted position; the upper member of said knife-jaw; means for holding it in relation to said lower member, and a belt-knife operated between the members of said knife-jaw.

4. A member for hide-working machinery comprising a shaft; a plurality of disks secured to or forming part of said shaft and each provided with a serrated perimeter; a ring for each of said disks the inner perimeter of which is serrated, and a layer of resilient material interposed between said disks and rings so that said rings may have independent movement of each other and in conformity with the thickness of the work under manufacture.

5. In a machine of the class described, the combination with a horizontally-adjustable jaw-bed provided with a rib circular in cross-section, of a knife-jaw constructed of an upper and a lower member; said lower member being provided with a slot in which operates the rib of said jaw-bed; means for adjusting the members of said knife-jaw in relation to each other, and means for adjusting said knife-jaw in relation to said jaw-bed through the medium of the lower member of said knife-jaw, and the belt-knife operating between the members of said knife-jaw.

6. In a machine of the class described, the combination with a member, of a knife-jaw designed to have tilting movement upon said member and comprising an upper and a lower member; means for adjusting the members of said knife-jaw in relation to each other so as to provide for wear; means for adjusting said knife-jaw in relation to said member through the medium of the lower member of said knife-jaw; the belt-knife operating between the members of said knife-jaw, and means for horizontally adjusting said belt-knife so as to maintain its edge substantially in a fixed path of movement.

7. In a machine of the class described, the combination with a horizontally-adjustable member, of a knife-jaw designed to have tilting movement upon said member and comprising an upper and a lower member; means for adjusting the members of said knife-jaw in relation to each other so as to provide for wear; means for adjusting said knife-jaw in relation to said member through the medium of the lower member of said knife-jaw, and means for horizontally adjusting said belt-knife so as to maintain its edge substantially in a fixed path of movement.

In testimony whereof I have signed my name to this specification, in the presence of two subscribing witnesses.

JAMES WILLIAM DECKERT.
